UNITED STATES PATENT OFFICE.

LAURENCE J. WINCHELL, OF NEWKIRK, OKLAHOMA.

NAIL-DRIVING TOOL.

Application filed March 25, 1926. Serial No. 97,307.

The present invention relates to nailing and stapling devices and is more particularly adapted to a nail driving tool.

One of the important objects of the present invention is to provide an implement of the above mentioned character which will save considerable time and labor in nailing metal pan forms used in concrete floor constructions, shingles, roofing, laths, and the like.

10 Another object of the invention is to provide a nail driving tool which will permit nails to be driven into places which are ordinarily difficult to reach when hammering a nail in the ordinary manner.

15 A further object is to provide a nail driving tool which includes a barrel having a magazine arranged in the lower end thereof, a nail holding magazine being associated with the hammer barrel and communicating

20 at its lower end therewith, a slidable plunger being arranged within the barrel and forming a means for driving the nail which is positioned in the bottom of the magazine into the object or article which is to be secured.

25 A cut off means is arranged adjacent the lower end of the nail holding magazine for preventing the delivery of the nails to the magazine of the barrel, means being associated with said aforementioned cut off means and arranged in the path of the sliding plunger whereby the cut-off means is moved to an inoperative position when the plunger moves downwardly in the barrel on its hammer stroke simultaneously causing another nail to be delivered to the magazine.

30 A still further object is to provide a nail driving tool of the above mentioned character which is simple in construction, inexpensive, strong and durable and further well adapted to the purpose for which the same is designed.

35 Other objects and advantages of the invention will become apparent from the following description taken in connection with the accompanying drawing.

In the accompanying drawings wherein like reference characters indicate corresponding parts throughout the several views:

40 Figure 1 is a side elevation of the nail driving tool embodying my invention.

45 Figure 2 is a similar view taken at right angles thereto.

50 Figure 3 is a sectional view taken approximately on line 3-3 of Figure 1.

Figure 4 is a similar section taken approximately on line 4-4 of Figure 1, and

55 Figure 5 is a detail perspective view of the spring strip showing the cut off and the releasing member associated therewith.

60 In the drawings, wherein for the purpose of illustration is shown the preferred embodiment of my invention, the numeral 1 designates generally my improved nail driving tool, the same comprising the elongated 65 barrel 2. For the purpose of convenience, the lower portion of the barrel is designated as the nail receiving chamber, and the same is indicated by the numeral 3. Adapted for 70 slidable movement through the barrel is the plunger rod 4. A weighted handle 5 is carried upon the upper end of the plunger rod 4.

75 A nail holding magazine 6 is provided in its outer side with the longitudinally extending slot 7, and this magazine is removably secured along the outer side of the barrel 2 in spaced relation thereto in the manner as is more clearly illustrated in Figure 1. A bracket 8 provides a means for supporting 80 the upper end of the nail holding magazine 6. The lower end of the magazine 6 is curved inwardly and extends around the outer curved face of a suitable casing 9 which is also secured on the outer side of 85 the barrel 2 as is clearly shown in Figure 4. The purpose of the casing 9 will be herein-after more fully described.

90 The upper portion of the nail receiving chamber 3 is provided with the elongated cut out portion 10 which provides an entrance for the chamber, and as is also shown in Figure 4, the lower curved end of the nail holding magazine 6 extends into the upper portion of the slot or cut out portion 10. An 95 angularly disposed guide 11 is secured to the barrel 2, and the same extends upwardly from the entrance of the chamber 3 as is clearly shown in Figures 1 and 4.

100 The heads of the nails 12 are disposed within the magazine 6, the shanks and the points of the nails extending outwardly through the longitudinal slot 7 and the nails are adapted to move downwardly in the magazine by gravity. For the purpose of further 105 assisting in the feeding of the nails to the nail receiving chamber of the barrel, I provide a block 13 which is slidable on the magazine and is adapted to engage the uppermost nail engaged in the magazine, this 110

block being attached to one end of a spring 14 which is coiled about a suitable pin 15. This pin extends transversely between the sides of the casing 9 and said casing provides 5 a means for receiving and housing the coil spring.

An elongated flat strip of resilient metal designated by the numeral 16 is disposed against the outer face of the barrel 2, the 10 upper end of the spring strip being secured to the barrel as at 17. A lateral extension 18 is formed on the outer side edge of the spring strip 16 at its intermediate portion thereof and this extension is disposed inwardly to 15 provide what I term as the cut off 19. This cut off extends into the guide chute 11 through the medium of a slot 20 provided therefor in the side of the chute and as is clearly illustrated in Figure 4, the cut off 19 is 20 preferably located within the chute 11 at a point adjacent the upper portion of the entrance 10 and coacts with the shank of the nails in preventing the lowermost nail in the magazine entering the barrel and the nail 25 receiving chamber formed in the bottom thereof.

A lug 21 is formed on the inner face of the spring strip 16 adjacent the lower end thereof, and this lug is provided with the 30 nose 22 for a purpose hereinafter to be more fully described.

This lug is adapted to extend through the longitudinally extending slot 23 provided therefor in the nail receiving chamber 3 of the barrel 2 so that the nose portion 22 will be disposed in the path of movement of the sliding plunger 4. The lug is preferably formed on the lower end of the spring strip 16 so as to be disposed below the entrance 10, in the manner as is also clearly illustrated in Figure 4.

A suitable handle 24 is secured on the upper end of the barrel 2 and extends transversely therefrom.

45 The operation of my improved nail driving tool may be briefly stated as follows: The magazine 6 is filled with nails so that the heads of the nails are disposed within the magazine and the pointed ends thereof project outwardly through the slot 7. The weight of the spring actuated block 13 will engage the uppermost nail and normally exert a downward pressure thereon so as to assure the positive feeding of the nails downwardly in the magazine.

Assuming that one nail is properly positioned in the lower end of the nail receiving chamber 3, and with the plunger 4 shown in the position in Figure 4, upon the down or hammer stroke of the plunger, the lower end of said plunger will move downwardly in the barrel and into the nail receiving chamber 3, and when the head of the plunger engages the nose 22 of the lug 21, it is obvious that as the hammer plunger moves down-

wardly through the barrel, the spring strip 16 will be swung outwardly so that the lug 21 will be moved out of the slot 23 and simultaneously, the cut off 19 will also move outwardly through the slot 20 thus permitting 70 the lowermost nail in the magazine 6 to be disposed in the entrance 10 and against the portion of the plunger which extends across the entrance.

Upon the upward sliding movement or return of the plunger 4 in the barrel 2, the spring strip will return to its normal position so that the lug 21 will project into the chamber 3 and the cut off 19 will again be disposed within the chute 11 so as to prevent any more nails being delivered to the nail receiving chamber or barrel and when the lower end of the plunger is disposed above the entrance 10 the nail which remained in the entrance while the plunger was driving the nail already positioned in the lower end of the chamber into the object, will fall into the chamber so that the lower end of the plunger may strike the head of said nail and drive the same into the object which is to be nailed.

It will thus be seen from the foregoing description, that I have provided a novel nail driving tool which will save considerable time and labor in nailing various objects or 95 articles, and furthermore only one nail at a time will be delivered to the nail receiving chamber of the barrel thus assuring the positive and efficient operation of the tool. The simplicity in which my improved tool is 100 constructed, enables the parts to be readily and easily accessible, and furthermore there will be no possibility of the nails clogging up in the magazine or in the nail receiving chamber of the barrel.

While I have shown the preferred embodiment of the invention, it is to be understood that minor changes in the size, shape and arrangement of parts may be resorted to without departing from the spirit of the invention and the scope of the appended claim.

Having thus described the invention, what I claim as new and desire to secure by Letters Patent is:—

A nail driving tool of the class described 115 comprising an elongated barrel, the lower end thereof being provided with a nail receiving chamber, said barrel having an entrance formed in the side thereof at the upper portion of the aforementioned chamber, a plunger slidable in the barrel, a nail holding magazine supported at the side of the barrel, the lower end of the magazine communicating with said entrance, a guide chute extending laterally from the barrel around 125 said entrance, a spring strip secured at its upper end on the outer side of the barrel, a lateral extension formed on the intermediate portion of said strip, the end portion of said extension being disposed inwardly through 130

the sides of the chute adjacent the aforesaid entrance to provide a cut off for preventing the delivery of the nails from the magazine to the barrel through said entrance, 5 and a laterally extending lug carried by the lower end of the spring strip, said lug being provided with a beveled nose and extending into the nail receiving chamber in the path of the sliding plunger, said lug adapted to 10 be moved outwardly of the barrel by the plunger on its down stroke for simultaneously releasing the cut off means, whereby

the lowermost nail in the magazine will be delivered to said entrance, said cut off being returned to its normal position for closing 15 the entrance when the plunger becomes disengaged from the nose on the lug during its upward stroke, whereby the nail positioned in the entrance will be delivered to the nail receiving chamber of the barrel when the 20 lower end of the plunger is disposed above the entrance.

In testimony whereof I affix my signature.
LAURENCE J. WINCHELL.
